HIS ATTORNEY.

UNITED STATES PATENT OFFICE

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY

IMPLEMENT RETAINER

Application filed July 6, 1929. Serial No. 376,408.

This invention relates to pneumatic tools, but more particularly to implement retainers for tools of this type.

One object of the invention is to prevent adherence of the yieldable buffer element to the head of the tool.

Other objects will be in part obvious and in part pointed out hereinafter.

In the drawings illustrating the invention 10 and in which similar reference characters refer to similar parts,

Figure 1 is a sectional elevation of the front end of a pneumatic tool having the invention applied thereto, and

15 Figures 2, 3 and 4 are perspective views of the details of the retainer.

Referring to the drawings, A designates the cylinder of a pneumatic tool having a piston chamber B in which is disposed a reciprocal hammer piston C for delivering 20 blows of impact to a working implement D, the shank end E of which extends into the front end of the piston chamber B. The working implement D may be of any known 25 type having a collar F at the juncture of the body portion of the working implement and at the shank E.

In the construction shown, the front end of the cylinder A is provided with an enlarged 30 bore G to receive a bushing H which serves as a guide for the shank E of the working implement.

The front end of the cylinder A is provided with exterior threads J on which is threaded 35 a head K having a wall K' at its front end in which is formed an aperture L through which the body portion of the working implement D extends.

The head K forms a receptacle for cushioning means adapted to cooperate with the collar F of the working implement for cushioning the blows of the working implement. The cushioning means illustrated comprises a rubber buffer O preferably in the form of a 40 single piece having a longitudinal slot P so that when used with a working implement having a cutting bit of larger diameter than the body portion of the working implement, the buffer O may be spread to readily dispose 45 it about the working implement.

In order to distribute the force of the blows of the working implement over the entire area of the buffer O a bushing Q in the form of half sections R is disposed between the rearward end of the buffer O and the collar F. 55 The bushing Q has an interior shoulder S against which the collar F may impact. The bore T in the bushing Q of which the shoulder S forms one end may be of suitable depth so that the working implement D will be capable of a certain degree of reciprocation relatively to the bushing.

Heretofore, in devices of this type employing rubber buffers as a cushioning medium for the working implement, it has been found 60 that after some use and upon exposure to a considerable number of heavy blows of the working implement, the rubber frequently adheres to its container, such as the head K. This is objectionable for various reasons but chiefly because of the considerable amount of time required to remove the buffer from the head whenever the buffer becomes unfit for use.

The present invention contemplates the 65 prevention of this objectionable condition, and to this end the retainer is provided with a sleeve U in the form of a pair of half sections V which are disposed within the head K to encircle the buffer O and also the bushing Q. Preferably the sleeve U is provided at its front end with a lateral flange W which lies against the wall K' of the buffer O to prevent the buffer from being squeezed into the 70 aperture L. Similarly, at the rearward end of the sleeve U is formed a lateral shoulder X which forms an abutment for the rearward end of the bushing Q. The head K is 75 preferably threaded on the end of the cylinder A to the point at which the flanges W and X bear firmly against the wall K' and the front end of the cylinder A respectively, thus preventing endwise movement of the sleeve U in the head K.

Any suitable means may be provided for preventing the unthreading of the head from the cylinder A. The means illustrated consists of a spiral spring Y which encircles the cylinder A and has hooked portions Z and b 80

which engage notches *c* and *d* of the head *K* and the cylinder *A* respectively.

In practice the present invention has been found to function in an unusually satisfactory manner since it entirely eliminates contact between the buffer *O* and the head *K* and therefore prevents adherence of the buffer to the head. Although the force of the blows of the working implement applied to the buffer may cause said buffer to adhere to the sleeve *U*, this will in no wise hinder the ready removal of the head *K* from the cylinder nor the removal of the head from the working implement. When this condition does occur the head *K* may be removed from the cylinder in the usual manner and thereafter the sleeve sections *V* may be removed from the buffer and a new buffer substituted to replace that previously used.

20 I claim:

1. In an implement retainer for pneumatic tools, the combination of a cylinder and a working implement extending into the cylinder, a collar on the working implement, a head secured to the cylinder for retaining the implement in the cylinder, a rubber buffer in the head to form a yieldable abutment for the collar, and a sleeve disposed in the head to prevent contact between the buffer and the head, said sleeve bearing with its ends against the head and the cylinder to maintain said sleeve against endwise movement in the head.

2. In an implement retainer for pneumatic tools, the combination of a cylinder and a working implement extending into the cylinder, a collar on the working implement, a head for retaining the working implement in the cylinder, a rubber buffer in the head forwardly of the collar to cushion the movement of the working implement, means interposed between the collar and the buffer to distribute the force of the blow of the implement over the entire end area of the buffer, a sleeve disposed in the head to form a container for the buffer and the said means, and a flange at one end of the sleeve forming an abutment for the buffer and preventing squeezing of the buffer from the head.

3. In an implement retainer for pneumatic tools, the combination of a cylinder and a working implement extending into the cylinder, a collar on the working implement, a head for retaining the working implement in the cylinder, a rubber buffer in the head forwardly of the collar to cushion the movement of the working implement, means interposed between the collar and the buffer to distribute the force of the blow of the implement over the entire end area of the buffer, a sleeve comprising a pair of half sections disposed in the head to form a container for the buffer and the said means, and lateral shoulders on the ends of the sleeve to hold the said

means and the buffer against endwise movement with respect to the sleeve.

4. In an implement retainer for pneumatic tools, the combination of a cylinder and a working implement extending into the cylinder, a collar on the working implement, a head for retaining the working implement in the cylinder, a rubber buffer in the head forwardly of the collar to cushion the movement of the working implement, means interposed between the collar and the buffer to distribute the force of the blow of the implement over the entire end area of the buffer, a sleeve encircling the buffer and said means, means for preventing free endwise movement of said means and said buffer in the head, and a recess in the first said means to permit limited free movement of the working implement in the head.

In testimony whereof I have signed this specification.

FRANCIS A. JIMERSON.
